UNITED STATES PATENT OFFICE.

PAUL MAUSER, OF OBERNDORF-ON-THE-NECKAR, GERMANY.

BOX-MAGAZINE FOR FIREARMS.

1,129,884.

Specification of Letters Patent.

Patented Mar. 2, 1915.

Application filed November 24, 1913. Serial No. 802,763.

To all whom it may concern:

Be it known that I, PAUL MAUSER, subject of the King of Wurttemberg, residing at Oberndorf-on-the-Neckar, in the Kingdom 5 of Wurttemberg, Germany, have invented certain new and useful Improvements in Box-Magazines for Firearms, of which the following is a specification.

The invention relates to a cartridge magazine for a pistol and resides broadly in the fact that the front portion of the bottom plate is guided by the lateral ribs of the magazine and constitutes a resilient locking means which, in the closed position, is disposed in front of the correspondingly formed guiding ribs.

In the drawing an embodiment of the invention is shown by way of example.

Figures 1 and 2 show synoptically the 20 lower portion of the pistol magazine constructed in accordance with the invention, with two different positions of the bottom plate. Figs. 3 and 4 are bottom views of the bottom plate and of the magazine without the latter. Fig. 5 is a longitudinal section through the magazine with the bottom plate.

The magazine *a* is provided at the lower edge, with ribs *b* in known manner, on 30 which the bottom plate *c* is guided by the edges of the bottom plate overlapping the ribs. The front portion of the bottom plate is formed as a T-shaped portion *c*¹ by two lateral angular cuts, and is connected to the

remainder of the plate by a resilient tongue 35 *c*². This portion *c*¹ is provided with lateral flaps *c*³ (Fig. 3) which when the bottom plate is slid over the magazine, slide on the latter's guiding ribs (Fig. 1) and as soon as the said plate is in place, drop in behind 40 suitably formed ribs *b* (Fig. 2). The bottom plate is thus securely retained on the magazine and can only be separated therefrom by raising the locking portion *c*¹ and simultaneously withdrawing the bottom 45 plate.

Owing to the fact that according to the invention the locking means is formed by the bottom plate itself a substantial simplification is effected over known constructions 50 in which separate locking means were fixed on the bottom plate.

What I claim as my invention and desire to secure by patent is:

A cartridge magazine for firearms comprising a magazine body having lateral ribs, a bottom plate guided on said ribs and lateral flaps on said bottom plate, said flaps, in the lock position, engaging openings in 55 said ribs and thus holding said bottom plate 60 on said magazine body.

In testimony whereof I have affixed my signature in presence of two witnesses.

PAUL MAUSER.
